UNITED STATES PATENT OFFICE.

WILLIAM J. PARSONS, OF MONTAGUE, MASSACHUSETTS, ASSIGNOR TO THE MILLERS FALLS COMPANY, OF MILLER'S FALLS, MASSACHUSETTS.

CHUCK.

SPECIFICATION forming part of Letters Patent No. 660,121, dated October 23, 1900.

Application filed April 2, 1900. Serial No. 11,059. (No model.)

To all whom it may concern:

Be it known that I, WILLIAM J. PARSONS, a citizen of the United States of America, and a resident of Montague, in the county of Franklin and State of Massachusetts, have invented 5 certain new and useful Improvements in Chucks, of which the following is a specification.

My present invention relates more especially to chucks provided with three or more jaws and without the usual socket into which the jaws are ordinarily drawn.

My special improvements consist of a novel arrangement of the jaws in connection with 15 a truncated cone-follower and other parts, as will be hereinafter more particularly explained.

In the drawings, Figure 1 is a sectional view of the operative parts of the chuck. Fig. 2 20 is a sectional view on the line 2 2 of Fig. 1. Fig. 3 is a sectional view on line 3 3 of Fig. 1. Fig. 4 is a view of the lower end of the cone and jaws with the spindle A and the cap-piece C removed. Fig. 5 represents the truncated 25 cone-follower D. Fig. 6 represents one of the jaws E.

The chuck consists, essentially, of the following parts: the spindle A, having the threaded part a, which threads in the cap-piece C and which has its inner end adapted 30 to fit the hole d', made in the bottom of cone-follower D, as indicated by a'. The cone-follower D is shown in Fig. 5, where the sides of the cone are represented by d² and the slots 35 for the jaws are indicated by d. The shape of the jaw is well shown in Fig. 6, in which the front or jaw proper is represented by e, the inside edge by e', the connecting-strip by e², and the end piece by e³. The piece e² is riveted 40 to the jaw proper or secured in any convenient manner, as shown by e⁴. The other end of the piece is also secured to the end piece e³ as desired. The three parts may be made all of one piece of metal, if desired. In the 45 slots d of the cone D, near the small end of the cone, is placed the spring f, held in place by a hole d⁴, drilled in the cone a little wider than the width of the slot d and deeper than said slot into which the spring sets, (see 50 Figs. 3 and 5,) each slot having its spring. A flat or other form of spring may be used,

though I prefer the spiral form, as shown. The jaws are placed over the slots d, and it will be observed that the part e⁵ of the jaw E will rest on the small end of the cone D, 55 that the part e² of the jaw will rest in the slot d, while the end piece e³ will extend down on the large end or bottom of the cone, as shown in Fig. 4. It will be noticed that the forward end of the part e² will rest on the spring f 60 and will be held in place by the action of the shell B, which is formed interiorly for a suitable distance to loosely fit the larger end of the cone, and then tapering down smaller and smaller till it ends at the exterior end opening 65 of the shell. (See b' b².) The cap C is preferably screwed to the end of the shell at b.

The operation of the chuck when completed is substantially as follows: The spindle A being screwed outward the cone-follower D, 70 carrying the jaws E, retires into the shell B, thus allowing the jaws E to open to receive the article between them. The spindle is then turned, forcing the cone-follower outwardly in the interior of the shell B. As the 75 cone advances the points of the jaws E are forced together by the action of the shell, and the article inserted between the jaws is securely held. Upon screwing the spindle in the opposite direction the jaws will open and 80 the article will be released.

The action of the spring f upon the jaw, in connection with the peculiar shape of the interior of the shell, as described, tends to cause the cone to retire inwardly as the spindle is 85 removed and the jaws to expand as they withdraw with the cone-follower. The spring f also tends to steady the part e² of the jaw. The inner end of the spindle might be suitably secured in the hole d' in the larger end 90 of the cone-follower. If this were done, the result of it would be simply this, that the cone-follower would be drawn inwardly by a positive movement in the withdrawal of the spindle. In case no springs were used 95 this might be advantageously done, though I prefer the arrangement shown as being simpler and all in all better for the purpose intended.

If the springs or one or more of them were 100 to break or become inoperative from any cause, the jaws would still open and the chuck

could be efficiently used, though not of course quite as quickly.

The inner or larger end of the cone loosely fits the inner internal recess of the shell, the 5 jaws fitting into the slots d of the cone, with the springs f pressing upward or outward on the jaws near the upper end of the slot, keeping the inner end of the jaw even with the bottom or inner end of the cone, and consequently 10 pressing against the interior of the shell. These peculiarities acting together make a remarkably simple, strong, and effective working chuck and overcome many of the objections found in prior constructions.

15 I do not confine myself to the exact form of parts described, as these may be varied without departing from the spirit of my invention.

Having now described my invention, what I claim, and desire to secure by Letters Patent 20 of the United States, is—

1. The spindle A, having the screw-threaded end a ; the shell B, provided with the cap C; the movable truncated cone-follower D, provided with the slots d ; the jaws E, suitably 25 formed to be held in the said slots d , and the springs f , all arranged, combined and adapted to operate substantially as described.

2. In a chuck the movable truncated cone-follower D, having the slots d ; in combination 30 with the jaws E, and the springs f , substantially as set forth.

3. The combination, in a chuck, of the shell B, formed interiorly as described, with the movable truncated cone-follower D, having 35 the slots d , the jaws E, adapted to fit and be held in position by the action of said slots and the interior of said shell substantially as specified.

4. The combination, in a chuck, of the shell B, a suitable movable follower, having suitable slots for the jaws; suitable jaws adapted to fit into the said slots and springs arranged to rest in said slots underneath the said jaws and, in connection with the said shell to close and open said jaws by the action of a suitable 45 spindle operating upon the inner end of the follower, all arranged and adapted to operate, substantially as and for the purposes set forth.

5. In a chuck, the combination, of a movable truncated cone-follower, provided with suitable slots; jaws formed to fit into and be held in place by said slots; springs beneath the jaws and near the smaller end of said cone and within said slots; and a suitable 55 shell adapted to coöperate with the said cone and jaws, substantially as and for the purposes herein set forth.

6. In a chuck, the combination of the movable truncated cone-follower D, having suitable slots d^2 , and a hole d^4 , to each slot greater in diameter than the width of the slot; the springs f , supported in said holes d^4 , and jaws E, consisting of the part e , adapted to rest on the small end of said cone and to extend outwardly therefrom and having the piece e^3 , adapted to enter said slots and provided with the end piece e^5 , all substantially as and for the purposes set forth.

Signed by me at Montague, Massachusetts, 70 this 28th day of March, A. D. 1900.

WILLIAM J. PARSONS.
